SWITCHING MECHANISM

Judson O'D Shepherd, Atlanta, Ga.

Application July 19, 1941, Serial No. 403,080

16 Claims. (Cl. 179—27.54)

This invention relates to switching mechanisms and particularly to improvements in switching mechanisms used in automatic telephone systems.

An object is to simplify automatic switching mechanisms for use in the establishing of telephone connections, to reduce the cost of such mechanisms and to improve the operation characteristics thereof.

Heretofore automatic switches have been provided with certain mechanism momentarily employed for the manipulation of any one of a plurality of such switches and then reverted or restored for common use.

The present invention relates in general to such common operating mechanism and arrangements in which a plurality of switching devices of the cross-bar switch type are associated with common mechanisms which may be used momentarily for controlling the selective operations of such switching devices.

A feature thereof is a structure comprising a plurality of switching devices of the cross-bar type in which a plurality of vertical select bars may be arranged in horizontal rows and a plurality of horizontal holding bars are provided for each row of vertical select bars with contacts at each intersecting point of a vertical bar with a horizontal bar for the establishing of a connection between contacts of any intersecting point. The connection is effected by the operation of a corresponding vertical select bar and a horizontal holding bar. A common mechanism cooperates with said switching devices, whereby any one of said vertical select bars may be selected and operated for the establishing of connections between the contacts at the cross-point of said operated select bar and any one of the holding bars associated with the horizontal row of select bars in which the operated select bar is located when said holding bar is actuated.

Another feature is an arrangement in a structure of this kind in which each horizontal row of vertical select bars is divided in a plurality of individual groups of select bars, while a plurality of horizontal holding bars remains common to each horizontal row of such groups of vertical select bars and in which the common mechanism cooperates with these groups of vertical select bars whereby any one of the vertical bars in any group may be selected and operated for the establishing of a connection between contacts at the cross-point of said operated select bar and any one of the holding bars associated with the particular horizontal row of said groups in which

the selected vertical select bar is located, when said holding bar is actuated.

Still another feature is means to extend connections between a large number of lines, say 700, and trunks, say 100, or conversely, by means of a comparatively few operating magnets which may be 127 or even less, in comparison with 1100 required in current practice. With switching arrangements of this general type it is desirable to have off-normal contacts associated with each line which are maintained operated whenever a connection is extended to or from it. This invention provides such off-normal contacts for each line to be maintained so operated notwithstanding that there is no magnet individual to the line as is required with usual arrangements.

The invention has been illustrated in the accompanying drawings, in which:

Figure 1 shows in general the construction details of a switching device in accordance with the applicant's invention; while

Fig. 2 shows in a more diagrammatic form the arrangement of the switching device in accordance with the applicant's invention; and

Fig. 3 shows details of the selecting and operating arrangements for the crosspoints and the off-normal contacts individual to each vertical row of crosspoints.

For the sake of clearness in describing the applicant's invention, the above-mentioned individual groups of vertical select bars arranged in horizontal rows and associated sets of contacts may be referred to hereinafter by the general term "switching unit" and the remainder of the mechanism may be referred to in general as the common mechanism. It should, however, be observed that the individual switching units comprising a horizontal row of vertical select bars and associated contact sets are associated with an individual group of holding bars cooperating with these units. Considered in this light, each switching unit and a part of the associated holding bars may take the approximate form, as far as the general operation and construction are concerned, of a cross-bar switch structure of the type as disclosed in the patent to J. N. Reynolds 2,021,329, issued November 29, 1935. It should, however, be observed that the cross-bar switch structure of this patent refers to the select bars as horizontal bars and the holding bars as vertical bars, while in the applicant's switching units the vertical bars are the select bars and the horizontal bars are the holding bars. In the primary embodiment, consideration of the Reynolds switch, therefore, should be on the basis of it be-

ing rotated 90 degrees and suitably modified as will be understood from what follows.

If reference is now made to Fig. 1 of the drawings one of these types of switching units is illustrated in more or less diagrammatic form in this figure at 10 showing one of a plurality of vertical select bars 11 having operating fingers 12 and a horizontal holding bar 13 which may be operated by a holding magnet 14 to engage, by means to be described, a selecting finger of an operated vertical select bar to cause a connection to be established at the crosspoint of these bars between associated contacts springs such as shown at 9. It should be understood that this horizontal bar 13 and others like it may extend across all of the switching units in the horizontal row of such switching units. It is evident also that in accordance with the present invention the vertical bars in the switching units of each horizontal row may, if so desired, be arranged in a single continuous horizontal row of vertical select bars without departing from the spirit of the invention. However, it is thought that it will be sufficient for the clear understanding of the applicant's invention to consider in the following description the applicant's switching device as consisting of individual switching units 10 in connection with the other parts as described herein-after.

The terms vertical and horizontal in regard to the select bars and holding bars are merely used to define two directions at right angles and are not to be construed as a limitation with respect to these specific orientations, since obviously a frame of switching units will be operative as described if it is rotated through any angle in its plane.

This switching unit 10 may be provided with five vertical select bars operative in two directions in connection with ten horizontal holding bars operative in one direction to establish connections at crosspoints of these two types of bars. The switching units may be arranged in horizontal and vertical rows for operation by a common mechanism in accordance with the applicant's invention.

This common mechanism consists, in addition to the above-mentioned holding bars 13, of a vertical column rod 15 for each vertical row of switching units 10 having a selecting finger 16 for each horizontal row of switching units and operative by a column magnet 17. Each horizontal row of switching units is provided with a horizontal group rod 18 operated upon by a horizontal group magnet 19 and each switching unit is provided with an individual horizontal group rod 20 having five fingers 21. When a column rod such as 15 is rotated counter-clockwise, the fingers 16 will be placed in a position between associated levers 22 on rods 18 and levers 23 on rods 20 of the corresponding vertical row of switching units so that, for example, when the horizontal group magnet 19 is operated, the lever 22 will engage the finger 16 to cause it to engage the lever 23 to rotate the rod 20 in a direction so that the fingers 21 will be moved downwardly. Attached to the lower end of each column rod 15 is a lever 24 to operate on a pin 25 to rotate a horizontal rod 26 common to a vertical row of switching units and located below the lower horizontal row of switching units. This rod 26 is, therefore, rotated on the operation of the column magnet 17. To rod 26 are attached five operating fingers 28 which are located slightly above a series of horizontal unit rods 29, 30,

31, 32 and 33 extending the whole length across the vertical rows of switches. The rod 26 extends in front of individual bifurcated projections on the unit rods such as, for example, projection 34 on rod 30. That is, there will be provided five such fingers 28 for each vertical row of switching units. These unit rods 29 to 33 may be operated in either direction longitudinally by opposing magnets such as 36 and 37 as shown for rod 33. The rod 33 may be operated, therefore, towards the left by the magnet 36 operating on its armature attached to rod 33 and towards the right by magnet 37 operating on its armature attached to rod 33. In a similar manner other magnets, not shown, are provided for operating the remaining unit rods in opposite longitudinal directions. Associated with each projection such as 34 is a vertical shaft such as 39 for rod 30 having a lever 40 registering with a select finger 28 so that when a rod 26 is rotated and this finger enters the bifurcated projection 34, it also will enter a bifurcated extension 42 of the lever 40 and when the corresponding unit rod 30 is moved in one direction or the other, the shaft 39 will thereby be rotated in one direction or the other through the medium of the lever 40, bifurcated extension 42, the bifurcated projection 34 and the finger 28. Each shaft 39 is located opposite a corresponding vertical select bar 11 in each of the corresponding vertical rows of switching units 10 and will cause the associated vertical bar 11 to be rotated in one direction or the other with the shaft 39 through the medium of lever 43 having bifurcated extension 44 and the lever 45 on bar 11 having a bifurcated extension 46, provided the associated finger 21 has been lowered to enter these bifurcations 44 and 46 due to the rotation of the bar 20. Thus a vertical select bar 11 will be rotated to place the select fingers 12 in position to be operated upon by any horizontal bar 13 of the associated horizontal row of switching units to establish a connection between contacts such as 9 at the corresponding crosspoint of an operated select bar 11 and holding bar 13. It should be understood that each holding bar 13 may be provided with suitable T-shaped control levers such as 47 each for the purpose of operating either of two sets of crosspoint contacts.

The details of the crosspoint contact operating arrangements are shown by Fig. 3. The crosspoint contacts 9 comprise, for illustration, three fixed contact springs formed from horizontal members 60 and three movable springs 61 suitably mounted on, but insulated from, the frame of the switching unit. Two sets of these crosspoint contacts are arranged to be operated by a single lever 47 affixed to the holding bar 13. The lever 47 terminates in an operating head 51. Each set of contacts 9 has a contact card 63 of suitable insulating material engaging the movable springs of the contact assembly. The operating finger 12 is normally slightly above and between the contact cards. If the select bar 11 is rotated counter-clockwise, the operating finger will be placed over the left-hand contact card so that upon subsequent rotation of horizontal bar 13 to move the head 51 downwardly, the latter will engage operating finger 12 to cause it to engage the contact card 63 and close the left-hand contacts 9. Had the vertical select bar 11 been rotated clockwise, the right-hand contacts would have been similarly closed upon operation of horizontal bar 13. Should horizontal bar 13 be operated with verti-

cal select bar 11 in its normal position, neither contacts would be closed inasmuch as the select finger 12 would not be in position to engage the contact cards of either contact assembly. The bottom part of head 51 may have a recession at its center as shown so that the select finger 12 will not be engaged by said head when this finger is normal. It will be seen, therefore, that a single lever 47 will selectively operate either of two contact assemblies, depending upon the direction the vertical select bar 11 has been rotated to position the select finger.

In systems where switching devices of this type may be employed, so-called off-normal contacts are generally required. To provide such contacts for operation each time a connection is made at a crosspoint in any of the switching units an arrangement such as shown by Fig. 3 may be employed. A set of off-normal contacts 54 are provided for each vertical row of crosspoints in each switching unit with an operating rod 53 individual thereto, said rod extending vertically alongside the ten sets of crosspoints in the row. A collar 64 is provided on this rod for each set of crosspoints in the row and is adapted to be engaged by bracket 65 attached to the contact card 63 so that upon downward movement of any contact card in the row incident to closure of the corresponding crosspoints, the rod 53 will be moved downward to actuate the off-normal contacts 54. The rod 53 may, of course, be moved by closure of any particular crosspoint contacts without affecting the other crosspoints in the corresponding row since the rod 5 and collars 64 are adapted to move free of the brackets 65 of the other crosspoints.

While closure of three sets of contacts are indicated by Fig. 3 upon operation of a particular crosspoint, it will be understood that other numbers of contacts and contact arrangements may be employed. Likewise, while only two off-normal contacts are shown for illustration, other numbers of such contacts may be used. Also, the off-normal contacts may comprise make, break or transfer types of contacts, or combinations thereof, as required for circuit uses of the device.

Similarly, there may be provided off-normal contacts for each select bar 11. In this case as the select bar 11 is rotated in either of two directions to select associated cross-point contacts, two sets of off-normal contacts will be provided, one set for each vertical row of contact springs. This arrangement of off-normal contacts for each select bar 11 may be as shown at 56, that is, each bar 11 may be provided with a lever 57 which acts on off-normal contacts 58 when bar 11 is rotated counter-clockwise and which acts on off-normal contacts 59 when bar 11 is rotated clockwise. It is, of course, evident that other off-normal contact arrangements may be provided as desired for those operable by bar 11, and also for any or all of the magnets in these switching devices to operate when the magnets are energized. It seems unnecessary to illustrate such off-normal contacts for the magnets in the drawings.

It is to be understood that all of the operable select elements described may be provided with spring means, not shown, to tend to maintain them in their normal positions and, subsequent to the release of the magnets which effected their operation, they will be returned to their normal position by said spring means.

With these general descriptions of the operat-

ing mechanisms that may be employed to carry out the applicant's invention, a description will now be made of a specific arrangement of switching units 10 and a common mechanism for operating contact springs in any one of said switching units by means of said common mechanism. To this end, Fig. 2 has been prepared to show in diagrammatic form an organization of switching units suitable for this purpose. In this figure two switching units 100 and 101 have been shown in one horizontal row and below this two other switching units 102 and 103 have been shown of another horizontal row. It may be assumed, for example, that these switching units form part of a system having a capacity of seven hundred line connections which would require seventy ten-by-ten switching units, that is, these units may be arranged in seven vertical rows and ten horizontal rows with, for example, switching units 100 and 101 being the first and second units in the upper or first horizontal row of seven units, and switching units 102 and 103 being the first and second units in the tenth or lower horizontal row of seven units. That would place units 100 and 102 in the first of seven vertical rows of units and units 101 and 103 in the second of the seven vertical rows of units with each vertical row containing ten units. If an arrangement was made to establish connections between seven hundred lines and one hundred trunks by the aid of ordinary crossbar switches there would be required seven hundred holding magnets and four hundred select magnets, if the crossbar switches were arranged under present practice as follows: For example, there may be employed in each of ten horizontal rows three crossbar switches having twenty holding magnets and ten select magnets each and one crossbar switch having ten holding magnets and ten select magnets or eleven hundred magnets in all. On the other hand by the use of this common mechanism an arrangement for the establishing of seven hundred connections would only require one hundred holding magnets, that is, ten holding magnets for each horizontal row of seven switching units, ten unit magnets located at the bottom of the ten horizontal rows of switching units, ten horizontal group magnets one for each horizontal row of units, and seven column magnets one for each vertical row of units, making a total of one hundred and twenty-seven magnets, which is a considerable saving in operating magnets and mechanisms for these switching units over those ordinarily required. If, therefore, the switching units are arranged in the manner shown in Fig. 2, the selecting of any of the contact springs at any crosspoint in any one of these seventy switching units may be accomplished as follows: For example, the column magnet 17 may be operated. This would select the first vertical row of ten switching units by placing the fingers 16 on the rod 15 in position to be operated upon to cause the operation of any of the horizontal rods 22 to select the particular switching unit in the first column of switching units. If it is then assumed that the horizontal group magnet 19 is operated to rotate the corresponding group rod 18 this rod 18 would, through lever 22, finger 16 and lever 23 cause the operation of the corresponding group rod 23 to cause this rod to place the fingers 24 in position to be operated upon for the selection of a vertical bar 11 in switching unit 102. Thus the operation of group magnet 19 will select the switching unit 102 in the first column in which are located the contacts to be operated. If now

one of the unit magnets, for example, 37 is operated, it will, through the medium of the finger 28, previously moved by bar 26 on the operation of the column bar 15 to its operated position between the projections 34 of unit rod 33 and between the projections 42 on the lever 40 of the shaft 39, cause the shaft 39 to be rotated in a counter-clockwise direction. Shaft 39 causes the rotation in the same direction of bar 11 of switching unit 102 through the lever 43 and its extension 44, finger 21 and lever 45 and its extension 46. Rotation of bar 11 will, therefore, select for subsequent individual selection the contacts in the corresponding vertical row of switching units 102 that are opposite the bar 11 when it is rotated in this direction as controlled by shaft 39. Had the unit magnet 38 been operated, the unit rod 33 would have been shifted in the opposite direction and thus cause bar 11 to be rotated in the opposite direction for selection of contacts in the adjacent vertical row in switching unit 102. If now the holding magnet 14 is operated to rotate bar 13, a finger 12 of bar 11 will be engaged by a head 51 of an operating projection 47 on bar 13 and the contact springs at the crosspoints of bars 13 and 11 will be operated in the manner described above. The holding magnet 14 will, of course, hold this connection established while the other magnets 17, 19, 31 and associated rods will be released and restored by their springs, not shown, to their normal positions for use in the establishing of connections in this or in any other switching units.

It should be understood that the invention is not confined to the particular number of switching units disclosed and that any other arrangement of switching elements in any desired order may be made without departing from the spirit of the invention. For example, instead of arranging the switching units in horizontal rows of seven switching units each and ten such horizontal rows for a seven hundred line capacity, switching units may be arranged in five horizontal rows with each horizontal row containing seven switching units each unit comprising ten vertical select bars running across twenty holding bars, thus making a saving of five group magnets 19 and the associated rods 18 and 20 of the common mechanism and yet have the switching device retain the seven hundred line capacity. Likewise, the horizontal rods 20 individual to each switching unit may be eliminated by providing their select fingers on rod 18 so that upon operation of magnet 19 all such fingers will be positioned to enable any select bars in the corresponding horizontal row of switching units to be operated by one of shafts 39. This would eliminate the need for column rods 15, and their magnets 17 would be needed merely to operate select bars 26. It also will be seen that the select fingers 12 may be mounted on shaft 39 which would eliminate the necessity of individual select bars 11, the horizontal group magnets 19, rods 15, 18 and 20 and the elements associated therewith. The magnets 17 would in this case, also, be needed only to actuate select rods 26. It is also apparent that magnets individual to each vertical shaft may be used to rotate said shafts individually rather than employing unit rods 20 to 33 and operating magnets therefor. Various combinations of the above and other modifications of the details of the arrangement may be made within the spirit and scope of the invention.

What is claimed is:

1. In a switching mechanism, a plurality of crossbar switching units arranged coordinately in horizontal and vertical rows, a plurality of select bars for each unit arranged in one co-ordinate direction, a plurality of holding bars arranged in the other coordinate direction and cooperating with said select bars, contacts at each intersecting point of said select and holding bars in each unit, means for establishing connections between the contacts at any point by the operation of a corresponding select bar and a corresponding holding bar, a mechanism including mechanical elements extending along and operatively associated with said units for selecting and mechanically operating a select bar in any of said units to the exclusion of other units, and means for operating a holding bar coordinately associated with the operated select bar to operate the contacts at the intersecting points of said select and holding bars.
2. In a switching mechanism, a plurality of crossbar switching units arranged coordinately in horizontal and vertical rows, a plurality of select bars for each unit arranged in one co-ordinate direction, a plurality of holding bars arranged in the other coordinate direction and cooperating with said select bars, contacts at each intersecting point of said select and holding bars in each unit, means for establishing connections between the contacts at any point by the operation of a corresponding select bar and a corresponding holding bar, a mechanism common to said units including mechanical elements coordinately arranged along, and operatively associated with, said units for selecting any particular one of said units and selecting and mechanically operating a select bar in said selected unit, and means for operating a holding bar coordinately associated with an operated select bar to operate the contacts at the intersecting point of said select and holding bars.
3. In a switching mechanism, a plurality of cross-bar switching units arranged coordinately in horizontal and vertical rows, a plurality of select bars for each unit arranged in one coordinate direction, a plurality of holding bars arranged in the other coordinate direction and cooperating with said select bars, contacts at each intersecting point of said select and holding bars in each unit, means for establishing connections between the contacts at any point by the operation of a corresponding select bar and a corresponding holding bar, a select rod for each unit operable to condition the select bars of its unit for selection and operation, a mechanism common to all of said units for operating the select rod of any unit to the exclusion of the select rods of all other units, a second mechanism common to all of said units functioning through an operated select rod for selecting and operating a select bar conditioned by said select rod, and means for operating a holding bar coordinately associated with an operated select bar to operate the contacts at the intersecting point of said select and holding bars.
4. In a switching mechanism, a plurality of cross-bar switches arranged coordinately in horizontal and vertical rows, a plurality of select bars for each switch arranged in one co-ordinate direction, a plurality of holding bars arranged in the other coordinate direction and cooperating with said select bars, contacts at each intersecting point of said select and holding bars in each switch, means for establishing connections be-

tween the contacts at any point by the operation of a corresponding select bar and a corresponding holding bar, a set of group select rods with each rod individual to a vertical row of switches, a set of group rods with each rod individual to a horizontal row of switches, means for operating said group select rods, means responsive to the coordinate operation of one of each of said two sets of group select rods for conditioning for operation the select bars in the switching corresponding to the intersecting point of said two operated group select rods, means including means common to all of said switches for operating a select bar among those conditioned, and means for operating a holding bar coordinately associated with an operated select bar to operate the contacts at the intersecting point of said select and holding bars.

5. In a switching mechanism, a plurality of cross-bar switches arranged in horizontal and vertical rows, a plurality of vertical select bars for each switch, a plurality of horizontal holding bars coordinately operative with said select bars, contacts at each intersecting point of said vertical and horizontal bars in each switch, means for establishing connections between the contacts at any point by the operation of a corresponding vertical select bar and a corresponding holding bar, a vertical shaft for each vertical row of select bars, means including means common to all of said switches for operatively associating the select bars of a particular switch with their respective shafts, means to operate a particular one of said last-mentioned shafts to operate the select bar operatively associated therewith, and means for operating a horizontal holding bar coordinately associated with an operated select bar to operate the contacts at the intersecting point of said select and holding bars.

6. In a switching mechanism, a plurality of cross-bar switches arranged in horizontal and vertical rows, a plurality of vertical select bars for each switch, a plurality of horizontal holding bars coordinately operative with said select bars, contacts at each intersecting point of said vertical and horizontal bars in each switch, means for establishing connections between the contacts at any point by the operation of a corresponding vertical select bar and a corresponding holding bar, a switch select rod for each switch, means including means common to said switches for operating a switch select rod, a vertical shaft for each vertical row of select bars extending in operative relationship with the switch select rod of each switch in the corresponding vertical row of switches, a group of select magnets common to all of said switches, means controlled by said means for operating the switch select rods to operatively associate the magnets and the vertical shafts to operate a shaft by a magnet, means cooperating with an operated switch select rod to operate a select bar in the switch corresponding to said operated switch select rod in response to the operation of a shaft, and means for operating a horizontal holding bar coordinately associated with the operated select bar to operate the contacts at the intersecting point of said select and holding bars.

7. In a switching mechanism, a plurality of cross-bar switches arranged in horizontal and vertical rows, a plurality of vertical select bars for each switch, a plurality of horizontal holding bars coordinately operative with said select bars, contacts at each intersecting point of said vertical and horizontal bars in each switch, means

for establishing connections between the contacts at any point by the operation of a corresponding vertical select bar and a corresponding holding bar, a switch select rod for each switch, a vertical group select rod individual to each vertical row of switches, means for operating each of said vertical group select rods, a horizontal group select rod individual to each horizontal row of switches, means for operating each of said horizontal group select rods, means responsive to the operation of a vertical group select rod and a horizontal group select rod for operating the switch select rod corresponding to the intersecting point of said vertical and horizontal group select rods, a vertical shaft for each vertical row of select bars extending in operative relationship with the switch select rod of each switch in the corresponding vertical row of switches, means including a set of magnets common to all of said switches cooperating as determined by an operated vertical group select rod to operate a shaft of the vertical row of switches corresponding to the operated vertical group select rod, means operated by said shaft cooperating with the operated switch select rod for operating a vertical select bar in the switch corresponding to said last-mentioned switch select rod, and means for operating a horizontal holding bar coordinately associated with an operated select bar to operate the contacts at the intersecting point of said select and holding bars.

8. In a switching mechanism, a plurality of cross-bar switches arranged in horizontal and vertical rows, a plurality of vertical select bars for each switch, a plurality of horizontal holding bars coordinately operative with said select bars, contacts at each intersecting point of said vertical and horizontal bars in each switch, means for establishing connections between the contacts at any point by the operation of a corresponding vertical select bar and a corresponding holding bar, a vertical group rod individual to each vertical row of switches, means for operating each of said vertical group rods, a horizontal group rod for each horizontal row of switches, means for operating each of said horizontal group rods, means responsive to the operation of a vertical group rod and a horizontal group rod for conditioning for operation the select bars in the switch corresponding to the intersecting point of said two operated group rods, a group of vertical shafts for each vertical row of switches with each shaft corresponding to a vertical select bar in each switch in said row, a group of select magnets for all of said switches, means responsive to the operation of a vertical group rod for operatively associating the group of shafts corresponding to this vertical group rod with said magnets whereby the operation of a magnet will result in the operation of a shaft, means functioning through said means for conditioning a set of select bars to operate one of said select bars in response to the operation of the shaft corresponding thereto, and means for operating a horizontal holding bar coordinately associated with an operated select bar to operate the contacts at the intersecting point of said select and holding bars.

9. In a switching mechanism, a plurality of cross-bar switches arranged coordinately in horizontal and vertical rows, a plurality of select bars for each switch arranged in one coordinate direction, a plurality of holding bars arranged in the other coordinate direction and cooperating with

said select bars, contacts at each intersecting point of said select and holding bars in each switch, means for establishing connections between the contacts at any point by the operation of a corresponding select bar and a corresponding holding bar, means common to said switches including a group of vertical and horizontal rods for conditioning for operation a particular switch corresponding to the intersecting point of an operated vertical and an operated horizontal rod, 10 an operating magnet for each of said rods, a set of shafts, means including means common to said switches for operating a shaft, means responsive to the operation of a shaft for operating a select bar in said conditioned switch and means to operate a holding bar coordinate associated with an operated select bar to operate the contacts at the intersecting point of said select and holding bars.

10. In a switching mechanism, a plurality of horizontal rows of vertical select bars, a plurality of horizontal holding bars common to each row for coordinate operation with said select bars in corresponding rows, contacts at each intersecting point of said vertical select bars and horizontal holding bars, means for establishing connections between the contacts at any intersecting point by the operation of a corresponding vertical select bar and a corresponding horizontal holding bar, a mechanism including mechanical elements extending along and operatively associated with said rows of vertical select bars operable to select and mechanically operate any vertical select bar in any of said rows, and means for operating a horizontal holding bar coordinate associated with an operated vertical select bar to operate the contacts at the intersecting point of said select and holding bars.

11. In a switching mechanism, a plurality of horizontal rows of vertical select bars each operable in two directions, a plurality of horizontal holding bars common to each row coordinate operatively with said select bars in corresponding rows, a pair of sets of contacts at each intersecting point of said vertical and horizontal bars, means for establishing connections between the contacts of one of the pair of sets of contacts at the intersecting point by the operation of the corresponding vertical select bar in one direction and the operation of a corresponding holding bar and for establishing connections between the contacts of the other of the pair of sets of contacts by the operation of said last-mentioned select bar in the other direction and the operation of said last-mentioned holding bar, means including a mechanism with mechanical elements common to, and extending along, said rows of select bars for selecting any select bar and mechanically operating it in either of its operable directions, and means for operating a holding bar coordinate associated with an operated select bar to operate the set of contacts of the pair at the intersecting point of said select and said holding bars predetermined by the direction in which said select bar has been operated.

12. The method of selecting and operating particular sets of contacts in a bank of coordinate arranged switches each with a plurality of coordinate arranged contacts which consists in mechanically conditioning a row of switches along one ordinate for selection, effecting a mechanical operation along the other ordinate for conditioning the switch corresponding to the crossing of said ordinates for selections within said switch, effecting a mechanical operation along the row of switches corresponding to said

first ordinate to effect the selection and conditioning for subsequent operation of a row of contacts in the direction of this ordinate within the conditioned switch and effecting a mechanical operation along the other ordinate within said switch to effect the selection and closures of the contacts corresponding to the intersection of said last-mentioned ordinate and the row of selected contacts.

13. The method of selecting and operating particular sets of contacts in a bank of switches arranged coordinate along ordinates M and N each with a plurality of contacts arranged coordinate along ordinates m and n, in which ordinates m and n are parallel respectively to M and N, which consists in mechanically conditioning the switches along ordinate M for selection, effecting a mechanical operation along ordinate N for selecting the particular switch of those conditioned which corresponds to the intersection of these two ordinates and conditioning said selected switch for selections within it, effecting a mechanical operation along the row of switches corresponding to ordinate M to effect the selection within the conditioned switch of a row of contacts along the m ordinate and effecting a mechanical operation along the n ordinate within said switch to select and close the set of contacts corresponding to the intersection of said last-mentioned ordinates.

14. The method of selecting and operating particular sets of contacts coordinate arranged in vertical and horizontal rows of groups in a bank which consists in performing mechanical operations along the vertical and horizontal ordinates for conditioning the sets of contacts of a group of contacts corresponding to the intersecting point of said ordinates for subsequent selection, performing a mechanical operation along the vertical ordinate for conditioning particular sets of contacts in said conditioned group for subsequent operation and performing a mechanical operation along the horizontal ordinate within said group for operating the set of coordinated contacts corresponding to the intersecting point of said last-mentioned ordinates.

15. A cross-bar switch comprising a plurality of primary circuits, a plurality of secondary circuits arranged transversely to and intersecting the primary circuits, contacts at each intersecting point operative to interconnect the primary and secondary circuits corresponding to said intersecting points, a select bar individual to each primary circuit momentarily operative to condition the contacts corresponding to its primary circuit for subsequent operation, a holding bar individual to each secondary circuit, means responsive to the operation of a holding bar while a select bar is operated to effect operation of the particular contacts of those conditioned for operation corresponding to the secondary circuit of last said holding bar and to maintain said contacts operated subsequent to the restoration of said select bar, means to operate any select bar momentarily, means to operate and maintain operated any holding bar, off-normal contacts corresponding to each primary circuit and means to operate the off-normal contacts of any primary circuit when that primary circuit is interconnected with any secondary circuit and to maintain them operated following the restoration of the operated select bar.

16. A cross-bar switch comprising a plurality of primary circuits, a plurality of secondary circuits arranged transversely to and intersecting

the primary circuits, contacts at each intersecting point operative to interconnect the primary and secondary circuit corresponding to said intersecting points, select bars momentarily operative individually to condition the contacts corresponding to any primary circuit for subsequent operation, a holding bar individual to each secondary circuit, means responsive to the operation of a holding bar while a select bar is operated to effect operation of the particular contacts of those conditioned for operation corresponding to the secondary circuit of said last holding bar and to maintain said contacts operated subsequent to the restoration of said select bar, means to operate any select bar momentarily, 15 means to operate and maintain operated any holding bar, off-normal contacts corresponding to each primary circuit and means to operate the off-normal contacts of a particular primary circuit in response to the actuation of any contacts for interconnecting that primary circuit with a secondary circuit whereby the off-normal contacts are controlled by the holding bar of the interconnected secondary circuit.

17. A switching mechanism including a plurality of cross-bar switches, a plurality of sets of contacts in each switch and means to select and operate any set of contacts in any switch, last said means including a plurality of magnets the total number of which is less than one-tenth the total number of sets of contacts in said switches.
18. A switching mechanism including a plurality of lines, a plurality of trunks in number smaller than the number of lines, off-normal contacts individual to each line, a plurality of cross-bar switches, a plurality of sets of contacts arranged in intersecting rows in each switch operative to selectively interconnect the lines and trunks, means common to said switches to select and operate the contact set at any crosspoint in any switch, last said means including operating magnets in number less than the number of lines, and means operative in response to the operation of a set of crosspoint contacts for actuating the off-normal contacts corresponding to the line interconnected with a trunk thereby.

JUDSON O'D SHEPHERD.
